SHAVER

Raymond A. Somers, Fairfield, and Robert J. Tolmie, Bridgeport, Conn, assignors to Sperry Rand Corporation, New York, N.Y., a corporation of Delaware

Filed Apr. 6, 1965, Ser. No. 84,635

Term of patent 14 years

(Cl. D95—3)

FIG. 1.

FIG. 2.

FIG. 1 is a front perspective view of a shaver, showing our new design;

FIG. 2 is a rear perspective view showing the bottom and the side opposite to the side shown in FIG. 1; and

FIG. 3 is a view similar to FIG. 1 and shows the cutter head of the shaver in a raised position.

The design is characterized by a casing of elongated rectangular configuration which is dominated by opposite faces each set between outwardly projecting longitudinal spaced side edges of the casing sidewalls with each face including a lower portion having peripheral marginal portions framing a rectangular-shaped gripping member and an upper portion comprising a flat rectangular surface spaced from the lower portion by an elongated strip extending transversely of the face between the side edges of the sidewalls.

We claim:

The ornamental design for a shaver, as shown and described.
